UNITED STATES PATENT OFFICE.

KENNETH E. STUART, OF NIAGARA FALLS, NEW YORK, ASSIGNOR TO HOOKER ELECTRO-CHEMICAL COMPANY, OF NEW YORK, N. Y., A CORPORATION OF NEW YORK.

ELECTROLYTIC METHOD AND APPARATUS.

Application filed March 5, 1925. Serial No. 13,285.

The invention relates to a method of and apparatus for the electrolytic decomposition of soluble salts, and is particularly useful in connection with the decomposition of the alkali-chlorides such as those of sodium and potassium. In the following description reference will be made to the decomposition of sodium chloride, but the invention is not limited to the decomposition of a particular salt.

Electrolytic operations of this nature are frequently carried out in cells of relatively great length as compared to their width or height, the electrodes comprising vertically disposed elements which are separated from each other by porous diaphragms extending longitudinally of the cell.

It is well known that in cells of this type no diaphragm, however perfect, can maintain absolute separation between the caustic soda and the chlorine, since the diaphragm must be porous in order to function at all, and this porosity will always permit of a certain back migration of sodium ions into the anode compartment, where they combine with chlorine to form sodium chlorate. This represents an impurity and a loss of efficiency. One of the most important factors affecting the back migration of sodium ions is the concentration of salt in the anode compartment. For this reason, it is desirable to keep the brine in this compartment as near the saturation point as possible. But if only saturated brine be fed to the cell, the brine in the anode compartment will be found after several hours to be considerably below the saturation point, due probably to the fact that the electrolytic action carries the salt through the diaphragm faster than the water passes through by ordinary percolation. The dilution of the brine does not go on indefinitely, but before the process becomes stabilized the dilution may reach such a point that chlorates are formed to an extent resulting in serious loss of efficiency.

If saturated brine is fed to the cell at one point only, as is now customary, the electrolyte will be near saturation only in the immediate vicinity of the infeed. At points remote from the infeed the electrolyte will be much below saturation, and at such places the formation of chlorates will be rapid. One way of minimizing this effect is to feed to the cell more salt than can be carried in

solution, the excess being in finely divided form and carried in suspension, as illustrated in Patent No. 1,423,584, granted to me on July 25, 1922. Whether undissolved salt is fed to the cell in suspension in the brine or not, the dilution within the cell will be minimized if circulation can be set up from the point of infeed toward the remote parts of the cell, and if excess salt is fed in suspension, it is all the more desirable that there should be such circulation, otherwise such salt may settle undissolved to the bottom of the cell.

Objects of this invention are to provide a method and apparatus for securing a circulation of the electrolyte within and longitudinally of a cell in such manner that a substantially uniform concentration of the electrolyte is maintained throughout the cell. More specifically an object is to provide a method of and apparatus for securing a longitudinal circulation of the electrolyte by means of the gaseous product given off at the anode. A further object is to provide a method of and apparatus for securing a solution of the excess salt carried into the cell in suspension.

A typical construction in accordance with this invention is illustrated on the accompanying drawings in which

Fig. 1 is a transverse section through the cell, taken on the line 1-1 of Fig. 2, and

Fig. 2 is a longitudinal central section on the line 2-2 of Fig. 1.

In the drawings, the numeral 1 designates the open-sided frame or body portion of the cell, which frame or body portion is formed of concrete or other non-conducting, chlorine-resistant material. Diaphragms 2 and perforated cathode plates 3 are applied to the sides of the frame 1, the cathodes being enclosed by side plates 4 which form the cathode compartments having outlets 5, 6 for caustic soda and hydrogen, respectively. A series of anodes, such as graphite blades 7, are arranged adjacent each of and parallel to the cathodes 3. The blades 7 are attached to graphite posts 8, and through the latter and ribbons 9, are connected to the busbars 10.

The exact construction of these parts is not material since the invention is applicable to any cell of relatively great length in which a series of anodes having active faces directed transversely of the cell are dis-

posed in longitudinal alignment. In accordance with my invention, I provide a circulation of the electrolyte longitudinally of the cell by diverting the chlorine evolved at the anodes along a submerged path extending longitudinally of the cell. As shown in Fig. 2, I may provide a false top 11 which extends across the cell below the level of the electrolyte and is spaced from the end walls of the frame 1. The lower face of the false top 11 is provided with channels 12 which slope upwardly from the ends of the top towards a restricted Venturi-shaped orifice 13, which is preferably at the middle point of the cell. The feed pipe 14 for delivering brine to the cell is arranged above and with its opening at the upper end of the orifice 13. The feed pipe 14 is supplied through a goose-neck 15 which forms a liquid seal preventing the escape of chlorine. As the chlorine can enter the lower end of the pipe 14, means are provided for preventing a back pressure which would break the seal in the goose-neck, which means may comprise, for instance, a chamber 16 between the goose-neck 15 and the pipe 14, which chamber is vented to the cell through the tube 17. The pipe 18 through which the chlorine is drawn off may be located at any convenient point.

It is well known that in cells of the type illustrated there is a transverse circulation due to the chlorine rising up the face of the anodes, the return flow being downward between the anode blades. In addition to this transverse circulation, a longitudinal circulation is set up by the stream of chlorine which escapes through the orifice 13, carrying with it the brine which is entrained as in an air lift pump. The brine which is lifted by the vigorous upward flow through the orifice enters the longitudinal passage lying between the false top 11 and the top member of the frame 1, in which passage the stream divides, flowing each way towards the ends of the cell from which points it returns to the main anode compartments, as indicated by the arrows in Fig. 2. Due to the location of the infeed pipe 14 beneath the surface and directly over the orifice, the excess salt in suspension in the infeed brine is immediately taken up by the upwardly rising stream of unsaturated brine.

Both the longitudinal circulation and the rapid solution of the excess salt, when combined with the transverse circulation, result in a nearly equal distribution, to every anode, of the fresh brine supplied through a single infeed.

It is to be understood that the invention is not limited to the specific form and arrangement of parts chosen for illustration, inasmuch as these are capable of being modified in numerous ways without departing from the spirit of my invention. For ex-

ample, in comparatively short cells, the chlorine stream could be deflected to a Venturi orifice located adjacent one end of the cell, and with such an arrangement or with that illustrated, the anodes may be of special design or arrangement to promote the transverse circulation of the brine. These and other modifications fall within the scope of my invention as set forth in the following claims.

75

I claim:

1. The method of maintaining a uniform concentration of the electrolyte in a cell having longitudinally arranged electrodes which comprises diverting the gaseous product evolved at an electrode along a submerged path extending longitudinally of the cell.

2. The herein described method which comprises establishing a circulation of the electrolyte within and longitudinally of the cell, and introducing super-saturated brine into said circulating stream of electrolyte at a point of low concentration.

3. A cell for the electrolytic decomposition of soluble salts, said cell being of relatively great length as compared to its width or height, and being of the type having longitudinally aligned electrodes with transversely directed active faces, characterized by the provision of means cooperating with the evolved gaseous stream to create a circulation of the electrolyte longitudinally of the cell.

4. The combination with an electrolytic cell of relatively great length and having upright electrodes provided with transversely directed active faces, of means diverting the gaseous decomposition product along a submerged path extending longitudinally of the cell.

105

5. The invention as claimed in claim 3 wherein said means comprises a false submerged top having an inclined channel in its lower face, said channel terminating at an orifice extending through said false top.

110

6. In an electrolytic cell, the combination with a relatively long and narrow frame, of a false top located below the normal level of the electrolyte, said top having an inclined gas channel in its lower face, an orifice through said top at the higher end of said channel, and means providing a passage for the return flow of electrolyte carried through said orifice by the gas stream.

115

7. In an electrolytic cell, means operative to establish a circulation of brine within the cell, and means for delivering infeed brine in counter flow to said circulating brine and at a point of relatively low concentration.

120

8. In an electrolytic cell, the combination with upright electrode members having active faces disposed transversely of the cell, of means operative to establish a circulation of the electrolyte longitudinally of the cell,

125

and means for introducing infeed brine into said circulating electrolyte stream at a point of relatively low concentration.

9. In an electrolytic cell, an open frame, a submerged top providing a passage between the top member of said frame and the anode compartment, an inclined channel provided in the lower face of said top, an orifice through said top at the upper end 5 of said channel, an opening spaced from said orifice and connecting said passage and anode compartment, and an infeed pipe having a submerged discharge opening positioned above said orifice.
10. In an electrolytic cell, an open frame, 15 a false top within said frame and having ends spaced from the end walls thereof, channels in the lower face of said top and sloping upwardly towards the longitudinal center thereof, a restricted orifice extending 20 through said top and communicating with said channels, and an infeed having a submerged discharge opening located above said orifice.

In testimony whereof, I affix my signature.

KENNETH E. STUART.
